US00D751794S

(12) **United States Design Patent**
Zenoff(10) **Patent No.:** **US D751,794 S**
(45) **Date of Patent:** **** Mar. 22, 2016**(54) **VISOR WITH A RECTANGULAR-SHAPED ELECTRONIC DISPLAY**(71) Applicant: **Andrew Zenoff**, San Anselmo, CA (US)(72) Inventor: **Andrew Zenoff**, San Anselmo, CA (US)(73) Assignee: **Beam Authentic, LLC**, San Anselmo, CA (US)(***) Term: **14 Years**(21) Appl. No.: **29/500,393**(22) Filed: **Aug. 25, 2014**(51) LOC (10) Cl. **02-03**

Primary Examiner — Karen E. Eldridge Powers*Assistant Examiner* — Jasmine Mlinarcik(74) *Attorney, Agent, or Firm* — Wilson Sonsini Goodrich & Rosati**CLAIM**

The ornamental design for a visor with a rectangular-shaped electronic display, as shown.

DESCRIPTION

FIG. 1 shows a perspective view of a visor with a rectangular-shaped electronic display;

FIG. 2 shows a front elevation view of the visor with a rectangular-shaped electronic display;

FIG. 3 shows a side elevation view of the visor with a rectangular-shaped electronic display; and,

FIG. 4 shows a top plan view of the visor with a rectangular-shaped electronic display.
